UNITED STATES PATENT OFFICE

148,892

DESIGN FOR A HOSE NOZZLE

Morris Swimmer, Pittsburgh, Pa.

Application April 16, 1946, Serial No. 128,626

Term of patent 14 years

(Cl. D91—1)

To all whom it may concern:

Be it known that I, Morris Swimmer, a citizen of the United States, residing at Pittsburgh, in the county of Allegheny and State of Pennsylvania, have invented a new, original, and ornamental Design for Hose Nozzles, of which the following is a specification, reference being had to the accompanying drawing, forming part thereof.

Figure 1 is a side elevational view of a hose nozzle, showing my new design.

Figure 2 is a rear elevation thereof.

I claim:

The ornamental design for a hose nozzle, as shown.

MORRIS SWIMMER.
